UNITED STATES PATENT OFFICE.

HARRY L. OWEN, OF YORK, PENNSYLVANIA, ASSIGNOR TO GENERAL ELECTRIC COMPANY, A CORPORATION OF NEW YORK.

MEANS FOR PREPARING ASBESTOS FIBER FOR INSULATING PURPOSES.

1,071,081.

Specification of Letters Patent.

Patented Aug. 26, 1913.

Application filed December 14, 1912. Serial No. 736,706.

To all whom it may concern:

Be it known that I, HARRY L. OWEN, a citizen of the United States, residing at York, county of York, State of Pennsylvania, have invented certain new and useful Improvements in Means for Preparing Asbestos Fiber for Insulating Purposes, of which the following is a specification.

This invention relates to the preparation 10 of asbestos fiber for use as an insulating material and has for its object the provision of means whereby asbestos fiber may be taken from a carding machine and brought to a condition suitable for application as an insulating covering for metallic surfaces.

My invention relates more specifically to the preparation of asbestos fiber in the form of a web or strip of carded, flocculent asbestos which is adapted to be wound upon 20 an electrical conductor. In my previous application, Serial No. 616,814, filed March 25, 1911, I have described and claimed such a strip of carded, flocculent asbestos wound into a roll with a supporting strip of flexible material, such as paper, between the turns. In the preparation of these rolls the asbestos comes from the doffing roll of 25 the carding machine in the form of separated flocculent strips and is delivered on 30 to strips of paper having substantially the same width as the strips of asbestos. The strips of paper are then wound up with the asbestos between the turns. In my previous application, Serial No. 473,243, filed January 20, 1909, I have described and claimed 35 a machine for winding the asbestos from the rolls upon the wire. The roll of paper with the asbestos upon it is unrolled and the strip of asbestos is caused to travel into contact with the wire and be spirally wound 40 thereon. It has been found in practice that the strip of asbestos fiber which comes from the carding machine often is placed irregularly upon the paper strip and will not, 45 therefore, be applied to the wire with uniformity. In carrying out my invention I provide means whereby the fiber strip as it comes from the carding machine is automatically placed regularly upon the paper 50 with their edges substantially parallel and the fiber incidentally condensed. In one specific embodiment of my invention I provide members which reciprocate between the adjacent strips so as to engage their edges 55 and arrange the strips uniformly and regu-

larly upon the paper. Incidentally the strips of asbestos are compressed or condensed in the direction of their width but this is not in all cases necessary although it is desirable where the strips of paper are 60 narrow for the purpose of economy of space.

Other objects and purposes of my invention will appear in the course of the following specification in which I have shown my invention embodied in concrete form for 65 purposes of illustration.

In the accompanying drawing illustrating one embodiment of my invention, Figure 1 is a side elevation of a machine embodying my improvement; Fig. 2 is a plan view of 70 the same; Fig. 3 is a detail of the reciprocating comb; Fig. 4 is a detail of the friction roll; Fig. 5 is a detail of the compressing means; and Fig. 6 is a diagram showing the various parts in relative positions. 75

Referring first to Figs. 1 and 2, 10 represents the doffing roll of a carding machine. This is a well known piece of apparatus and requires no description. This doffing roll is divided into sections as shown 80 in dotted lines in Fig. 2 so that the asbestos fiber will be delivered therefrom in separated strips as shown. The fiber is removed from the doffing roll by means of a reciprocating comb 11 pivoted at 12 and is 85 caused to reciprocate in any desired manner, as for instance by the rotary disk 13 having a pin and slot connection with an arm 14 which causes the arm 11 to rotate back and forth on its pivot in a well known manner. 90 As the asbestos leaves the doffing roll it is delivered to the conveying means which consists of a roller 15 and the tapes upon which the asbestos is mounted. It is while 95 the strips of asbestos are passing over this roller 15 that their edges are straightened and rendered parallel, and the strips are properly positioned with reference to the traveling tapes which are to receive them. The asbestos is also compressed and compacted, although as already explained this is not in all cases necessary although it would be practically impossible to arrange the fiber properly without compacting it to 100 a certain extent. This compacting mechanism is shown in Figs. 5 and 6 and consists of a plurality of plates 16 mounted upon a shaft 17, there being a plate between each two adjacent strips of asbestos. These 105 plates fit over the roller 15 and engage the 110

same, as shown in Fig. 6. The rod 17 is caused to reciprocate longitudinally in any desired manner, as for instance by means of a crank disk 18 having a pin engaging a yoke 19 on the end of the shaft. I have shown a plurality of pins 20 in the disk for engaging the yoke located at different distances from the center so as to vary the travel of the shaft 17 as desired. By referring to Fig. 5 it will be seen that as the shaft 17 reciprocates, the plates, which are in contact with the roller 15, will engage the edges of the strips of asbestos and to a certain extent compact the fiber so as to make the edges of the strips parallel and properly position them with reference to each other and also with reference to the traveling tapes. With the arrangement shown it will be noted that each plate, excepting, of course, the end plates, is located between two strips and engages first the edge of one and then the edge of the other. The amount which the fiber is shifted will depend upon the width of the strip and the travel of the shaft 17 upon which the members are mounted. This of course may be varied as desired.

In Fig. 6 the operation is shown in outline. Strips or tapes of paper 21 are wound into rolls and are supported in friction rollers of any desired construction, as, for instance, the construction shown in Fig. 4. The paper passes from this roll 21 through a chalk box 22 which properly prepares the surface to receive the asbestos and from there passes over a series of rollers 23, 24, 25, 26 and is wound up on the roller 27 which is likewise of the friction type. These rolls 23, 24, 25 and 26 regulate the speed of the paper and it is important that the speed of the rolls be such as to give the paper a speed corresponding to the rate at which the asbestos fiber is delivered from the doffing roll. The asbestos fiber coming from the doffing roll 10 is removed by means of the comb 11 and thrown on to the roll 15 which revolves in a direction to carry the fiber on to the paper tapes. As the asbestos passes over this roll the plates 16 engage the edges in the manner above described and arrange the strips as shown in Fig. 2. The asbestos then passes on to the paper between the rolls 26 and 28 and is then wound up with the paper in the manner described in my previous application above referred to. The rolls of paper and asbestos are then removed from the machine and used as insulating material or for any other purpose desired.

While I have described my invention as embodied in concrete form and as operating in a specific manner in accordance with the patent statutes, it should be understood that I do not limit my invention thereto since various modifications thereof will suggest themselves to those skilled in the art with-

out departing from the spirit of my invention, the scope of which is set forth in the annexed claims.

What I claim as new and desire to secure by Letters Patent of the United States, is:—

1. Means for preparing asbestos fiber for application to electrical conductors comprising a carding machine arranged to deliver carded flocculent asbestos in separated strips, conveying means for receiving said strips, and movable means for engaging the edges of said strips while traveling on said conveying means to make the edges thereof substantially parallel with each other.

2. Means for preparing asbestos fiber for application to electrical conductors comprising a carding machine arranged to deliver carded flocculent asbestos in separated strips, conveying means for receiving said strips, and reciprocating means for engaging the said strips while traveling on said conveying means to make the edges thereof substantially parallel with each other.

3. Means for preparing asbestos fiber for application to electrical conductors comprising a carding machine arranged to deliver carded flocculent asbestos in separated strips, conveying means for receiving said strips, and reciprocating members located between the strips on the conveyer so as to alternately engage the adjacent edges of the strips between which they are located to make the edges substantially parallel with each other.

4. Means for preparing asbestos fiber for application to electrical conductors comprising a carding machine arranged to deliver carded flocculent asbestos in separated strips, conveying means for receiving said strips, and a plurality of members one of which is located between each adjacent pair of strips so as to engage the edges thereof, and means for simultaneously reciprocating said members and causing them to alternately engage adjacent edges of the strips between which they are located.

5. Means for preparing asbestos fiber for application to electrical conductors comprising a carding machine arranged to deliver carded flocculent asbestos in separated strips, conveying means comprising a conveyer for receiving said strips and a plurality of tapes for receiving the strips from the conveyer, and reciprocating members mounted adjacent said conveyer to engage said strips while traveling on the conveyer and arrange the same in parallel relation for delivery to said tapes.

6. Means for preparing asbestos fiber for application to electrical conductors comprising a carding machine arranged to deliver carded flocculent asbestos in separated strips, conveying means comprising a conveyer for receiving said strips and a plurality of tapes for receiving the strips from the

conveyer, a plurality of members one of which is located between each adjacent pair of strips so as to engage the edges thereof, and means for simultaneously reciprocating said members to cause them to alternately engage adjacent edges of the strips between which they are located to arrange the same in parallel relation for delivery to said tapes.

In witness whereof I have hereunto set my hand this eleventh day of December, 1912.

HARRY L. OWEN.
